UNITED STATES PATENT OFFICE.

MONROE GUETT, OF HARTFORD, CONNECTICUT, ASSIGNOR TO HART & HEGEMAN MANUFACTURING COMPANY, OF HARTFORD, CONNECTICUT, A CORPORATION OF CONNECTICUT.

SNAP-SWITCH.

1,204,012.

Specification of Letters Patent. Patented Nov. 7, 1916.

Application filed December 27, 1915. Serial No. 68,916.

To all whom it may concern:

Be it known that I, MONROE GUETT, a citizen of the United States, residing in Hartford, in the county of Hartford and 5 State of Connecticut, have invented the following-described new and useful Improvements in Snap-Switches.

This invention relates to electric snap-switches designed for production at a minimum cost for material and assemblage, and to such end its object is to utilize sheet material substantially throughout the whole of the snap-mechanism and in such form as to be capable of expeditious manufacture in 15 automatic stamping or pressing machinery, and of rapid assembly, and with the fewest possible number of parts consistent with economy of material.

The invention comprehends various mechanical embodiments of the principles of production, construction and assemblage hereinafter fully explained and as pointed out in the claims appended hereto.

In the drawings: Figure 1 is a plan view 25 of a double-pole switch embodying my invention; Fig. 2 is a longitudinal section of Fig. 1 with parts broken out; Fig. 3 is a central section through the switch parts, showing the contact blade open; Fig. 4 is 30 the same view, closed; Fig. 5 is a perspective assembly of the base and rocking spring carrier; Fig. 6 a cross-section illustrating the journals of the three main parts; Fig. 7 is a detail of the crank shaft; Figs. 8 to 10 35 are details later identified; and Fig. 11 is a modified detail.

As common in the class of rocking spindle switches, the operated member of the present switch is a contact blade 1, which snaps into 40 alternate positions, in one of which it bridges two opposite contact terminals 2, and in the other of which it is separated from both terminals to interrupt the circuit at two points. The blade is carried by, but 45 insulated from, the rocking spindle, herein termed the crank shaft, and the latter is actuated by two push buttons, or equivalent means, the snap action being produced by the connecting parts which include a spring. 50 In the particular switch taken for illustration there are two contact blades, one at each end of the crank shaft, and two pairs of contact terminals, constituting a double-pole switch, but it will be apparent that the number 55 of poles is optional with the manufac-

turer and quite independent of the principles of construction constituting this invention.

The actuating mechanism whereby the push member or members controls the blade, 60 is comprised of but three main parts, each a simple sheet metal stamping, as follows,— a base or bracket 3, a spindle or crank-shaft 4 (bearing the contact blades) and a push-operated rocker 5—6. The sheet metal 65 bracket 3 is formed with a pair of opposite bracket-arms 3^a, punched to form two alined crank-shaft bearings 3^b (Fig. 9) which are provided with access slots 3^c to admit the journal portions 4^a (Fig. 7) of the crank 70 shaft 4. The latter, being a flat, sheet-metal stamping, as shown in Fig. 7, is introduced laterally through these slots and so as to engage by its edges, the edges of the hook-shaped portions constituting the bearings 3^b, 75 in which relation the crank-shaft is retained by its correlation to the other parts. One or both ends of the crank shaft is stamped with a two-armed enlargement or head 4^b, 80 forming its attachment with the blade or blades, the latter being slotted to fit the arms without contact and sandwiched thereon between insulating washers 7 and metal washers 8, which are all clamped firmly and permanently against the base of the head, 85 by upsetting or riveting the ends of the arms against the outermost washer, as shown in Fig. 6. Obviously, a single arm head or other means of attaching the blade to the arm, without electrical connection, can be 90 employed with similar effect, but the double-arm head is preferred on account of its obvious security and because the enlargement represented by the head forms a suitable shoulder for engagement with the outside 95 of the bracket arm to prevent endwise displacement of the crank shaft and thereby insures correct alinement of the blade with its contact terminals 2, notwithstanding excessive wear.

It will be noted that the crank-shaft and its blade-attaching arms or rivets, as well as its shoulder portions, are all in one piece, simultaneously produced in the stamping machine. The crank portion 4^c of the crank-shaft is disposed between the arms of the bracket and receives its throw from a stout helical spring 9 connected thereto in any suitable manner, as, for instance, by hooking the end of the spring through a hole 100 105 110

punched in the center of said crank portion. The other end of this spring is connected to the push-operated rocker or spring carrier and is adapted to be carried by it across the 5 plane of the crank shaft and far enough beyond to cause the crank to throw. This rocker is likewise formed of a sheet metal stamping and in the present case is made of two symmetrical duplicate parts 5 and 6, 10 placed together as indicated in Fig. 5, and fulcrumed on two studs 10, one on each arm 3^a of the base 1. The location of said stud fulcrums is central with respect to the throw of the crank shaft and between the base of 15 the mechanism and the crank shaft bearings. Such location, however, is subject to variation, as will become apparent from the further description of the device, and the fulcrum axis might be coincident with the 20 crank axis if desired, but it is desirable that the upper end of the spring be moved through as wide an angle as possible and for that reason the fulcrum is preferably as near to the base of the bracket as is indicated 25 in the drawings. The fulcrum stud 10 is produced on each of the arms 4 at the time the base 1 is blanked out of the sheet metal stock, and by extrusion of the metal, so that it is therefore integral with the bracket. 30 This is done by a suitable plunger, forming part of the die mechanism, and which by making the indentation 10° (Fig. 9) on one side of the blank forces a corresponding amount of metal into a die cavity of smaller 35 diameter on the other side. The two halves or parts of the spring-carrier are punched with holes conforming to their respective studs and are placed thereon with their in-turned arms 5^a and 6^a brought together so 40 as to form a single hook or hole 11 for connection with the actuated end of the spring 9, and the latter when attached to the said hook serves to hold the two parts of the carrier together and also in alinement with 45 each other, so that they form in effect a unitary structure. The arms of the carrier member which project from each side of its fulcrum, are provided with eyes 12, and the stamped sheet metal shanks of the push- 50 buttons are formed with outstanding lugs 13 to engage therewith. These lugs also assist in retaining the parts of the carrier together and upon their respective studs, as may also the crank portion of the crank 55 shaft which occupies substantially the full width of the space between the side plates of the rocker. By one or all of these agencies the two-part spring-carrying rocker member is retained in operating relation, in 60 which it may rock in either direction, under the force of one of the buttons, until it encounters and is stopped by the edge of the bracket base on one side or the other.

The spring 9, being normally under tension, exerts its force on the crank shaft to

hold it at all times firmly upon its hook bearings 3^b, on which it may either be caused to slide or rock as desired and according to the shape of the bearings. When the rocker carries the upper end of the spring across 70 the plane of the crank, the latter is thrown from one position to the other, either opening or closing the switch, and the extent of its throw is limited, in both directions, by stops, which, in the preferred structure, are 75 formed by the corners of the bracket base, bent up to form a pair of lugs 14 on each side, and which take the impact of the crank upon their edges. An alternative means of limiting the crank shaft throw is shown in 80 Fig. 11, wherein the two screws 15 which screw the bracket to the bottom of the insulating receptacle, 16, are made long enough for their projecting ends to serve as stops. The lug-form stops as first described, are 85 preferred because they may be made automatically in the press and of the same material as the bracket, and hence with greater economy, the process of assembling being also simple and quick. Such process may be 90 performed by first placing the two parts of the carrier on the lug 13 of the button shanks and then on their fulcrum studs 10, which can be done by slightly skewing the said parts when introducing them into the 95 bracket and without straining them or the bracket; the crank shaft is then placed between the stop lugs and in its hook bearings 3^b, and the spring is then attached to it and to the hook 11 of the rocker, which locks all 100 of the parts against any possibility of displacement. By the aid of suitable temporary holding appliances, these successive operations can be performed with great rapidity, and inasmuch as each part of the 105 switch is a simple stamping and can be rapidly and automatically produced from sheet stock, it will be evident that the cost of production of the switch is low while the resulting structure is manifestly strong and durable. 110

The bracket equipped with rocker, crank-shaft spring and buttons, is secured to the bottom wall of the receptacle 16, and the buttons introduced into the holes in the 115 plate 17, which guides them and in which they have a substantially rectilinear movement, due to the short arc through which the arms of the rocker are required to move. The contact blade is thereby brought into 120 alinement with the terminals 2 which are secured to the rim part of the receptacle by screws 19 inserted from the bottom in the usual way. The arms of the contact blade are formed at an angle to each other or in 125 the shape of an obtuse V, so that a line joining their two extremities is considerably removed from the axis of the crank-shaft, and by virtue of this shape both arms extend away from the bottom of the receptacle 130

when in the circuit closing position, as shown in Fig. 2, thereby eliminating the necessity of locating one of the contact terminals at or near the bottom of the receptacle, as heretofore the custom in switches of this general class. In consequence of this shape of blade, the said terminals may both be formed of similar simple stampings, as indicated in Fig. 8, and with their contact portions closely adjacent to their binding screws 20 for the wire connections, so that they are both thus composed of a minimum amount of metal, brass, and hence produced at the least cost.

15 It will be evident that the base bracket 3 may be made of various configurations to accomplish the purposes above described, and provide the open or hook bearings for the crank shaft and that the latter is similarly subject to variation from the particular contour indicated, while still preserving its interlocking relation to its bearings and the base, as above described, and eliminating special elements or special acts in its construction. The said shaft as shown can be completed in a single stroke of the stamping machine or press, ready to receive the contact members and their insulation. In the case of the single pole switch, one of 20 the heads 4^b can be reduced to such shape and size as will still constitute a shoulder on the shaft for the purpose above described, or it may be eliminated entirely, or left as shown in Fig. 7, without a contact 25 blade. It will be evident without explanation that the rocker member 5—6 could, if desired, be made of a single piece sheet metal stamping, joined at the hook 11, or elsewhere, but by dividing it into two parts, the sheet metal stock can be utilized with 30 less scrap and the result of a single piece can be secured by the locking effect of the spring and other parts as described.

It is thus apparent that the invention is 45 in no wise limited to the particular conformation of the principal parts but may comprehend other sheet metal forms having the same principles of structure and assemblage, and therefore I particularly claim 50 said invention as follows:

I claim:

1. In a snap switch, the combination of a stamped sheet metal bracket having hook 55 bearings formed therein, a crank shaft introduced laterally into said bearings, a tensioned spring connected by one end to said crank shaft, and actuating means connected to the other end of said spring and adapted to carry the same across the plane of said 60 crank shaft in either direction.

2. In a snap switch, a bracket member, a crank shaft member journaled therein, a rocker member fulcrumed on the base, each 65 of said members being formed of sheet metal stampings, in combination with a

spring secured by one end to the crank shaft and by the other end to said rocker member and adapted to be carried thereby across the plane of the crank shaft.

3. In a snap switch, a bracket provided 70 with bearings, a flat crank shaft member formed of stamped sheet metal engaging said bearings by its edge, means including a spring for imparting a snap movement to said crank shaft upon its said bearings, and 75 a contact blade carried by the crank shaft.

4. In a snap switch, the combination with a bracket having open bearings therein, of a crank shaft engaging said bearings and integral shoulders on said crank shaft for 80 preventing endwise displacement thereof.

5. In a snap switch, the combination with a bracket member and a crank shaft fulcrumed thereon, of a two-part rocker member also fulcrumed thereon, and a spring 85 connecting said shaft to the rocker and serving to lock the parts of the latter in their normal position.

6. In a snap switch, the combination of a sheet metal bracket having bearings therein 90 provided with access slots, a sheet metal crank shaft journaled in said bearings and introduced therein through said slots, a spring connected by one end to said crank shaft, and means for carrying the other end 95 of said spring across the plane of said crank shaft in either direction.

7. In a snap switch, a bracket provided with bearings having access slots, a flat crank shaft member formed of stamped 100 sheet metal engaging said bearings by its edge and introduced laterally therein through said slots, and means including a spring for imparting a snap movement to said crank shaft upon its said bearings. 105

8. In a snap switch, a base or bracket having arms provided with hook bearings, a stamped, flat, sheet-metal crank-shaft introduced laterally into said bearings, and integral shoulders on said crank shaft for 110 engaging said bracket arms to prevent endwise displacement of said shaft, in combination with a spring to operate said crank shaft in either direction.

9. In a snap switch, the combination of a 115 base provided with bracket arms having bearings with access slots and having integral fulcrum studs on their inner faces, a rocker having arms pivotally supported on said studs, a sheet metal crank shaft introduced into said bearings through said slots, contacts carried by said crank shaft, and a tension spring connecting said crank shaft and said rocker for holding said crank shaft and said rocker in extreme positions. 120

10. In a snap switch, the combination of a base provided with bracket arms having bearings with access slots and having integral fulcrum studs on their inner faces, a 125 rocker fulcrumed on said studs, a shoul-

dered, sheet metal crank shaft introduced into said bearings through said slots, contact blades carried by said crank shaft, stops on the base to limit the movement 5 thereof, and a tensioned spring connecting said crank shaft and said rocker and normally holding said crank shaft against said stops.

11. The combination in a snap switch of 10 a receptacle having short contact terminals

secured at opposite points near the rim thereof, a rotary shaft member mounted within the receptacle and carrying a V-shaped contact blade adapted to bridge said terminals, a spring to actuate said shaft 15 member and button-means to actuate the spring.

In testimony whereof, I have signed this specification.

MONROE GUETT.
